LOOM SHUTTLE

Carl D. Brown, Hopedale, Mass., assignor to Draper Corporation, Hopedale, Mass., a corporation of Maine

Substituted for abandoned application Serial No. 536,924, May 23, 1944. This application May 23, 1945, Serial No. 595,273

3 Claims. (Cl. 139—223)

The present invention relates generally to shuttles for automatic looms and, as illustrated herein, relates more particularly to means for reinforcing shuttle bodies adjacent the side delivery eye thereof.

This application is a substitute for applicant's forfeited application Serial No. 536,924, filed May 23, 1944.

In present day shuttles, a threading block is usually provided adjacent one end thereof and secured in position by a bolt extending through the shuttle and threading block and clamping the block in position between the front and rear walls thereof. The wood of the shuttle body is relatively thin at the front wall and the clamping pressure exerted on the head of the bolt by the nut is often times sufficient to cause the wood at this point to split or break and on some occasions the head of the bolt may even be pulled through the front wall.

In order to avoid such a condition, it has, heretofore, been proposed to reinforce the wood adjacent to the side delivery eye by inserting pegs of wood, metal, or other suitable material. These pegs have been satisfactory for varying periods but under most conditions these pegs loosen after the shuttle has been used for a period and thus are no longer effective to prevent splitting or breaking of the wood.

One object of the present invention is to provide a construction whereby the above mentioned difficulties may be overcome. To this end and in accordance with one feature of the invention, a peg formed of suitable material such, for example, as vulcanized fibre, is inserted into the body of the block adjacent to the side delivery eye in a position where the peg will be engaged by and locked in position by the clamping means. In the illustrated construction, two vulcanized fibre pins are used, both pins being cut away to a certain extent when the front wall is counterbored to receive the head of the clamping bolt. Thus, each pin is engaged by the head of the bolt and is prevented from loosening and pulling out of the shuttle.

With the above and other objects and features in view, the invention will now be described with particular reference to the accompanying drawing, which illustrates a preferred embodiment of the invention and in which—

Fig. 1 is a view in front elevation of a shuttle in which the present invention is embodied;

Fig. 2 is a fragmentary view partly in section and on an enlarged scale of a portion of the shuttle shown in Fig. 1; and

Fig. 3 is a sectional view taken along the line III—III of Fig. 2.

The illustrated shuttle comprises a shuttle body 10 having the usual filling carrier receiving recess 12 and a communicating cavity 14 for receiving a threading block 16 of any usual type. The shuttle is provided with a side delivery eye 18 defined between a pin 20 driven into the shuttle body 10, forming a bearing member for the running filling when the shuttle is picked in one direction and a pin 22 secured in the threading block 16, forming a bearing member for the running bearing when the shuttle is picked in the other direction. The shuttle eye 16 is maintained and clamped in the cavity 14 by a bolt 24 extending through the front and rear walls 26, 28 respectively, of the cavity 14. The bolt is provided at one end with the usual head 30 and at its other end with a nut 32. The head 30 and the nut 32 are located in counterbored openings 34, 36, respectively. The construction described above is old and well known in the art and need not be described in further detail herein.

As shown best in Fig. 3, the front wall 26 is drilled to receive posts or pegs 38, 40 formed of vulcanized fiber or other suitable material. The holes for the pegs are formed before the various cuts are made to receive the threading block 16 and the side delivery eye. The holes for the pegs are drilled from the bottom of the shuttle body and terminate just above the hole for receiving the bolt 24. The peg or post 38 is so located that the counterbored hole 34 for the head 30 of the bolt terminates in the upper end portion 35 of said peg 38 so that a portion of the head 30 seats in the cut away portion 42 of the peg 38. The peg 40 is substantially smaller in diameter than the peg 38 and is located close enough to the hole for the bolt 24 so that a portion of the head 30 will seat against a shelf 44 thereon formed when the hole 34 is counterbored.

The pegs or posts 38, 40 fit tightly into their respective holes and in addition are coated with glue to insure that they will stay in position. The pegs reinforce and strengthen the front wall 26 and prevent it from splitting or breaking during use. The head 30 of the bolt 24 fits into the cut away portions of the pegs which form an effective seat for said head and prevents the head 30 from being pulled through the wood when clamping pressure is applied by tightening the nut 32. The head 30 also prevents the pins from moving longitudinally or from turning so that any tendency of the pegs to loosen is substantially eliminated.

When the opening is formed in the front wall 26 for the side delivery eye 18 and during subsequent finishing operations, the wood adjacent to the peg 38 is cut away to receive the threading block 16. The peg 38 is also cut away at 48 to form a surface over which the running filling passes during operation of the shuttle. The fiber peg 38 forms a smooth even surface free from projecting fibers or splinters which would injure the running filling. The peg 38 thus not only provides a seat for the head 30 of the bolt 24 and reinforces the shuttle body but also provides a smooth surface over which the filling is guided as it passes from the side delivery eye.

Having thus described my invention, what I claim as new and desire to secure by Letters Patent of the United States is:

1. A shuttle comprising a shuttle body having a recess for receiving a filling carrier, a cavity communicating with said recess for receiving a threading block and a side delivery eye in the front wall of said shuttle body and communicating with said cavity, a threading block in said cavity, a pair of spaced pins in said front wall close to said side delivery eye and a bolt passing through a hole formed between said pins and through said threading block to hold said threading block in position, said pins each being provided with a shelf forming a seat for the head of said bolt.

2. A shuttle comprising a shuttle body having a

recess for receiving a filling carrier, a cavity communicating with said recess for receiving a threading block, and a side delivery eye in the front wall of said shuttle body and communicating with said cavity, a pair of spaced vertical pins in said front wall close to said side delivery eye, and a bolt passing through a hole between said pins and through said threading block to hold said threading block in position, said shuttle body being counterbored between said pins to receive the head of said bolt and to provide a seat for said head on each of said pins.

3. A shuttle comprising a shuttle body having a recess for receiving a filling carrier, a cavity communicating with said recess for receiving a threading block, and a side delivery eye in the front wall of said shuttle body and communicating with said cavity, a pin vertically mounted in the front wall of said shuttle body and forming at least a portion of one side of said delivery eye, a second pin parallel to said first pin and located inwardly therefrom, each of said pins having a cut away portion defining a flat seat, and a clamping bolt passing through a hole formed between said pins and through said threading block to hold said threading block in position, said flat seats on said pins being engaged by the head of said bolt and preventing radial and axial movement of said pins.
